ADJUSTABLE PICKING MOTION

Peter Emile Provost, Pawtucket, R. I.

Application February 14, 1942, Serial No. 430,984

4 Claims. (Cl. 139—150)

The present invention relates to new and useful improvements in pick motions and in particular to picking motions on automatic filling changing Draper looms, and comprises an improvement on my prior Patent No. 2,229,899, dated January 28, 1941.

An object of the present invention is to provide simple and practical means for adjusting the picker shoe on the picker stick, and which at the same time is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a sectional view through the picker stick with the shoe shown in plan.

Figure 2 is a side elevational view thereof.

Figure 3 is a sectional view taken substantially on a line 3—3 of Figure 1, and

Figure 4 is a sectional view taken substantially on a line 4—4 of Figure 2.

Referring now to the drawings in detail the numeral 5 designates the picker stick having the bolt 6 extending therethrough and to the lower end of which the strap 7 is attached by the clamp 8.

The picker shoe is designated at 9, which includes the shank portion 10 having the vertical slot 11 formed therein through which the bolt 6 is inserted and held in position by the head 12 of the bolt.

The shank 10 is of channel shape in cross-section and has its upper end offset from the picker stick, as shown at 13, and threaded through the offset upper end 13 is an adjusting screw 14 adapted to bear against the tongue 15 positioned in the channel of the shank, the tongue also being of channel shape in cross-section and in which the picker stick is positioned. The set screw 14 is secured in locked position by a jam nut 16. The tongue 15 is also formed with a vertical slot 17 to freely accommodate the bolt 6.

Positioned between the tongue 15 and the picker stick 5 is a plate 18 having prongs 19 adapted for embedding in the picker stick, the plate also having an opening 20 to receive the bolt 6.

The upper end of the tongue 15 is formed with a shoulder 21 underlying a shoulder 22 formed

on the upper end of the plate 18 and through which a set screw 23 is threaded, the lower end of the screw being adapted to bear upon the shoulder 21, as shown to advantage in Figures 2 and 3 of the drawings. The set screw 23 is secured in adjusted position by a jam nut 24.

From the foregoing it will be apparent that the shoe 9 may be adjusted vertically on the picker stick by loosening the bolt 6 and loosening the set screws 14 and 23, and the tongue 15 may likewise be vertically adjusted relative to the picker stick, as well as with respect to the shoe.

Accordingly, the shoe and tongue may be adjusted on the picker stick as the circumstances require.

It is believed the details of construction, operation and advantages of the device will be readily understood from the foregoing without further detailed explanation.

Having thus described the invention what I claim is:

1. In a device of the class described, a picker stick, a shoe adjustably positioned on the stick, said shoe including a shank having a vertical slot therein, a bolt fixed to the stick and positioned in said slot for vertically adjusting the shoe on the stick, a tongue positioned between the shank and the stick, and including a part resting on the shank and means including vertical and horizontal set screws bearing respectively against the top and side of the tongue and adapted for securing the same in vertically adjusted position relative to the stick.

2. In a device of the class described, a picker stick, a shoe adjustably positioned on the stick, said shoe including a shank having a vertical slot therein, a bolt vertically fixed relative to the stick and positioned in said slot for vertically adjusting the shoe on the stick, a tongue positioned between the shank and the stick, a shoulder on the upper end of the tongue overlying and resting on the shank, a vertical set screw carried by a part fixed relative to the picker stick and bearing against the shoulder of the tongue, and a horizontal set screw carried by the shank and bearing against the tongue.

3. In a device of the class described, a picker stick, a shoe adjustably positioned on the stick, said shoe including a shank having a vertical slot therein, a bolt carried by the stick and positioned in said slot for vertically adjusting the shoe on the stick, a tongue loosely positioned on the bolt at one side of the shank, a plate positioned between the tongue and the picker stick and secured against movement relative to the

latter, a shoulder on the upper end of the tongue resting on the shank, a shoulder on the upper end of the plate overlying the first-named shoulder, a set screw carried by the second shoulder engaging the first shoulder for vertically adjusting the tongue relative to the stick, and a set screw carried by the shank and engaging the tongue to secure the same against relative vertical movement.

4. In a device of the class described, a picker stick, a shoe adjustably positioned on the stick, said shoe including an upstanding channeled

shank having a vertical slot, a tongue of channel shape in cross-section positioned in the shank, said tongue receiving the stick and said tongue also having a vertical slot aligned with the slot of the shank, a plate interposed between the tongue and the stick and anchored to the latter, a bolt carried by the stick and inserted through said slots, and means operating in vertical and horizontal directions against the tongue for adjustably securing the shank and tongue longitudinally of the stick.

PETER E. PROVOST.
